PRINTING DIE PROTECTION MEANS

Jacob W. Ogden, Springdale, Conn., assignor to
Pitney-Bowes Postage Meter Co., Stamford,
Conn., a corporation of Delaware

Application June 9, 1938, Serial No. 212,647

1 Claim. (Cl. 101—216)

This invention relates to a rotary printing device which is adapted to print an impression, the detail of which will be different when the device is operated during a normal power printing operation from that of an impression which is taken from the printing die when it is in a rest position.

The invention is particularly related to a metered mailing machine such as used for the printing of postage stamp impressions upon mail matter, wherein the printing die includes an indicia, postmark and value printing portions.

In view of the fact that in the normal order of printing stamp impressions by means of a metered mailing machine, the value of each impression is registered through the operation of totalizing mechanism concealed within a meter unit, some means is provided for the protection of the printing die to prevent the taking of impressions therefrom without first actuating the totalizing mechanism. Various devices commonly known as die protectors have been in use for this purpose.

In the device of the present invention, a novel form of die protection is offered without the use of die protection devices, in that the die face is engraved in such manner that an impression taken therefrom, while in a rest position, will present a distorted appearance, and such an impression would be easily identified as fraudulent by postal inspectors. But, while it would be impossible to take a normal impression with the printing die in a rest position, the distorted portions of the die will disappear in an impression which is taken when the machine is operated under normal power conditions. The result is accomplished by altering the relative speed between the drive of the printing die and an impression roller which cooperates therewith or the mail feed means.

It is one object of the invention therefore to provide in a rotary printing device, means whereby an impression taken under power will differ in detail from an impression taken from the printing die while it is in a rest position.

It is another object to provide a printing die with a normally distorted die face, which, when the relative speed between the drive of the printing die and that of an associated drive means is different, the distorted surface will be controlled so as to print a normal undistorted stamp impression.

With the foregoing and other objects in view which will appear as the description proceeds, the invention resides in the combination and ar-

angement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a plan view of a metered mailing machine generally indicating the printing devices and drive members;

Fig. 2 is a front elevational view of Fig. 1;

Fig. 3 is a vertical sectional view taken along the line 3—3 of Fig. 1;

Fig. 4 is a fragmentary view of a variable speed drive means;

Fig. 5 is a face view showing the result of an impression taken from a printing die while in its rest position, and which particularly illustrates the distorted nature of the impression; and,

Fig. 6 is a view similar to that shown in Fig. 5, showing a stamp impression printed by the printing die under power.

Referring to Fig. 1, the machine disclosed includes a rotary printing member 10 and an impression roller 11, each of which may be driven from a power driven pulley 12 through a bevel gear drive 13 and spur gear 14.

Letter feed means is also provided which comprises feed rollers 15 having a driving connection with the spur gear 14, which feed means is adapted to convey a letter indicated at L, to the printing and impression rollers. Before the letter L reaches the printing and impression rollers, it engages a tripping member 16, which through suitable clutch control means is adapted to trip a clutch member indicated at 17. The letter L, upon engaging the printing and impression members, will receive the printed indicia stamp and postmark impressions shown in Fig. 6, and will then be removed by means of driven rollers 18—19 to suitable stacker means. The printing of the stamp indicia and postmark impressions are effected by means of the indicia die 19 and postmark die 21, which are carried by the rotary printing die 10.

Also during the printing cycle of operation 50 the value of the stamp printed will be automatically registered in a suitable totalizer unit which is sealed within a meter unit 22, the said totalizer unit being controlled by the drive indicated at 23.

The foregoing mechanism is well known in the art of metered mailing machines and further description is not deemed necessary.

Referring now to the particular means for accomplishing the result of this invention, the indicia and postmark printing dies 19 and 21 have their printing surfaces specially designed and engraved so as to produce a distorted impression of the character shown in Fig. 5. Here it will be noted that the postmark is oval shaped and that the stamp is greater in its horizontal dimension than that of the impression shown in Fig. 6. It will also be noted that the vertical lines are given less thickness than the horizontal lines. Said shape and thickness of the vertical lines produce the distorted appearance previously referred to, which, if an impression were fraudulently taken therefrom, could be easily identified. Such a distorted impression will not result however, when the article or mail to be printed is passed through the machine during a normal machine cycle of operation.

The controlling means for changing what would normally be a facsimile of the form of the indicia and postmark dies or distorted impression of the form shown in Fig. 5, to a normal indicia and postmark stamp impression of the form shown in Fig. 6, comprises the driving of the rotary printing member 10 at a greater speed than that of the impression roller 11. This speed ratio is produced, as best shown in Fig. 3, by the drive of gears 24 and 25. The gear 24, which is associated with the impression roller 11, is of larger diameter than the gear 25, which is fixed to a shaft 26 which carries the printing member 10. The gear 24 is driven through the spur gear drive 14 from the main drive 12—13.

The ratio of said gears 24 and 25 will effect an

increased speed of rotation of the printing member which obviously will effect a slight skid of the die printing surface over the article which is being printed. But, when designing the vertically disposed lines of the printing dies, allowance is made for the skid and the resulting impression is reduced to a normal well proportioned stamp impression with lines of substantially even weight.

While the increased speed of the printing die 10 will effect a reduction in the horizontal dimension of the printed impression, it is apparent that a decrease in the speed of the printing die will result in an increase in the horizontal dimension and that the line design of the die must be adjusted accordingly.

By substituting a pair of elliptical gears 27, 28 for the spur gears 24, 25, it is possible to vary the speed of rotation of the printing member with relation to the speed of the feed rollers, to thereby effect a variable skid which may be found desirable in some forms of stamp design.

Having described the invention, what is claimed is:

In a device for printing a postmark and indicia stamp upon letters, a rotary printing member having a postmark die and an indicia die thereon, said postmark die comprising an oval configuration, an impression roller, and a drive for said rotary printing member to rotate same at a speed which is greater than the speed of the impression roller, whereby the printed impression of the oval shaped postmark die will become circular shaped and the indicia impression will be proportionately shorter than the indicia printing die.

JACOB W. OGDEN.
